UNITED STATES PATENT OFFICE.

EDWIN H. BENNERS, OF ELIZABETH, NEW JERSEY.

SIDE FRAME FOR CAR-TRUCKS.

No. 903,535.

Specification of Letters Patent.

Patented Nov. 10, 1908.

Application filed January 20, 1908. Serial No. 411,618.

To all whom it may concern:

Be it known that I, EDWIN H. BENNERS, a citizen of the United States, residing in Elizabeth, county of Union and State of New Jersey, have invented certain new and useful Side Frames for Car-Trucks, of which the following is a specification.

This invention is a side frame for car trucks, the same appertaining more especially to frames of that class which, in the main, are cast in one piece.

An object of the invention is to facilitate the operation of assembling the bolster relative to the side frames, and to retain the bolster in position after it shall have been inserted in said frames.

An important advantage secured by my invention is that bolsters of different weights and sizes may be readily placed in position and retained within truck side frames of a standard size.

The side frame of this invention is designed and proportioned throughout its several elements with a view to reducing the weight to a minimum, while securing the strength required to withstand the load and the side or end thrusts, an especially important feature being the ability of the side frame to resist distortion which would result in disalignment of the axle boxes.

Each side frame is, preferably, of that class wherein the frame is cast in one piece. As will presently appear, said frame comprises an arched top member, a bottom member, columns connecting the top and bottom members, and stay members inclined with respect to the top and bottom members, each of said members being of channeled form in cross section.

According to one embodiment of the invention, the columns are parallel to each other, the space between said columns exceeding the width of the bolster which is to be used in connection with the truck by inserting its end portions into the vertical openings which are formed between the aforesaid columns. For retaining the bolster in position, it is provided on its respective sides with grooves, each groove being formed by parallel flanges or ribs, the latter being, preferably, integral with the bolster. Co-operating with the grooved bolster are guide members which are made separate from the frame and are attached to the columns thereof, said members protruding from the op-

posing faces of said columns, and fitting in the grooves of the bolster. Furthermore, it is preferred to insert the guide members in the columns, and to this end, each column is provided with a recess bounded on all of its sides by walls, the latter being engaged by the edges of one guide member in such manner as to effectively retain the guide member in position, although it is preferred to fasten each guide member to a column by one or more bolts.

From the foregoing it should be noted that a grooved bolster may have its end portion inserted into the opening of the side frame below the guide members, thus easily introducing said bolster, after which the bolster is raised into the required position. At this time, the guide members enter the grooves in the bolster, and they operate thereafter to retain the bolster against side-wise or endwise motion relative to the side frame, said bolster being free, however, to move or play vertically within said truck and within the limits determined by the usual springs.

In the accompanying drawings, I have illustrated one practical embodiment of the invention, but the construction shown therein is to be understood as illustrative, only, and not as defining the limits of the invention.

Figure 1 is a side elevation, partly in section, of a side frame embodying the present invention. Fig. 2 is a plan view with parts broken away to show other parts in horizontal section. Fig. 3 is a vertical cross section on the line 3—3 of Fig. 1. Fig. 4 is a detail view of a part associated with a brake-beam. Fig. 5 is a horizontal section on the line 5—5 of Fig. 1. Fig. 6 is an inverted or bottom plan view of a part of the right hand end portion of the arched top member. Fig. 7 is a cross section through one of the inclined struts or members on the line 7—7 of Fig. 1.

The side frame, A, shown in the drawings has substantially all of its main parts cast in a single piece of metal, but it is not desired to confine the present invention to a one piece frame, for the reason that certain features of said invention may be used in connection with built-up frames. As shown, said frame consists of a top member, a bottom member, b, the columns, c, c', and the inclined struts or brace members, d, d'.

The top member, a, is arched from end to

end thereof, although the end portions of said top member are flattened on their lower sides, as at a' , for the reception of the pedestals or axle boxes, one of which is indicated 5 in part by the reference character B at the left hand portion of Fig. 1. As is usual in the art, the pedestals or axle boxes are applied to the flattened end portions, a' , of the top member, a , and they are fastened in position by suitable bolts, the bolt holes being indicated at a^2 , in the top member, a . Said top member is of channeled form in cross section, see Figs. 2 and 3, and it is preferred to provide said top member, a , with depending flanges, a^3 , from which extend reentrant flanges, a^4 .

The bottom member, b , is of channeled and skeletonized cross section, as shown in Figs. 1 and 3. The member, b , is provided 20 with upstanding side flanges, b' , and with intermediate webs, b^2 , thus producing a structure possessing the requisite strength with a decrease in the weight of metal.

The columns, c , c' , join the top member, a , 25 with the bottom member, b , and as shown, these columns are equidistant from the middle portion of the frame. Said columns are parallel to each other, and they are of channeled form in cross section, see Fig. 5. Each 30 column is shown as provided with side flanges, c^2 , and the middle portion of the column is provided with slots or openings, c^3 , which tend to decrease the weight of the metal. The columns c , are joined at their 35 lower portions with the bottom member, b , and the inclined struts, d , d' , whereas the upper portions of the columns are joined with the channeled top member, a . The struts d , d' , extend from the end portions of 40 the bottom member, b , to the end portions of the arched top member, a , so as to join with or merge into said members, a , b . Each inclined member is provided with side ribs, d^2 , thus producing a strut of channeled cross 45 section, see Fig. 7.

C designates a spring plank which is fitted in the lower part of the opening which is formed in the side frame by and between the columns, c , c' , the top member, a , and the 50 bottom member, b . This spring plank may be of any usual or preferred construction, and it rests upon the flanges and webs, b' , b^2 , of the bottom member.

At the end portions of the spring plank 55 are the angle reinforcing plates, D, one of which is shown in section in Fig. 1. The vertical member of this angle plate engages with the inner face of one of the columns, whereas the horizontal member of said angle 60 plate rests upon the bottom member, b . The angle plate is fastened in position by bolts, e , which are shown in dotted lines in Fig. 3, and in full lines in Fig. 5, said bolts passing through the vertical member of the angle 65 plate and also through suitable lugs, e' ,

which are provided on the column. Through the horizontal member of the angle plate passes a vertical bolt, f , the latter extending through a web of the bottom member, b , whereby each angle plate, D, is held securely 70 in position.

As is usual in the art, the set of springs, shown partly in Fig. 1 and indicated by the reference character, E, is seated upon the spring plank, C, and these springs coöperate 75 with a bolster, F, for the purpose of holding the latter normally in a working position within the side frame. Said bolster, F, may be of the usual or any preferred construction known to those skilled in the art, 80 but in Fig. 2 of the drawings, I have shown a bolster adapted to be made of cast steel. The bolster is provided at each end portion with grooves, f' , each of said grooves being 85 between a pair of parallel ribs or webs, f^2 , which are preferably integral with said bolster.

The width of the space between the opposing faces of the columns, c , c' , exceeds the total width of the bolster, F, that is between the flanges, f^2 , on one side of the bolster and the corresponding flanges, f^2 , on the opposite side thereof. This proportion of the vertical opening in the frame, A, to the width of the bolster, F, enables an end 90 portion of said bolster to be thrust into or through the lower part of the aforesaid vertical opening in the side frame, the springs, E, being temporarily out of place.

For the purpose of retaining the bolster 100 against endwise displacement, and to guide said bolster in its vertical travel or play within the upper part of the aforesaid vertical opening, I employ the guide members, G, one of which is provided on the inner 105 face of each vertical column, c , c' , whereby said guide member is adapted to occupy one of the vertical grooves, f' , of the bolster.

The members, G, are arranged in corresponding positions at the upper portions of 110 the columns, c , c' , and on the opposing faces thereof, said members being a short distance below the top member, a . The guide members, G, are parallel to each other, and they protrude from the opposing faces of the columns, whereby said guide members are fitted 115 snugly in the grooves which are provided in the sides of the bolster, F.

Each guide member, G, is preferably cast in a single piece of metal, and it is furthermore preferred to inset each guide member in one of said columns for the purpose of rigidly fastening the guide member to the column in a way to preclude displacement of said guide member from said column. As 120 shown in Figs. 1 and 2, each column is provided with a vertical recess, h , which is bound on four sides by the marginal walls or shoulders, h' , the recess being closed in 125 all its portions, except on the inner face of 130

the column. The guide member, G, is reduced on one side so as to form the seat portion, g, which is bound by the shoulders, g', and this seat portion is fitted snugly in the recess, h, of the column, whereby the shoulders of the guide member engage with the shoulders, h', of the recess. The seat portion, g, of said guide member fits snugly in the recess, h, so that it cannot move in any direction therein, and when the bolster is in position so that the guide member will engage with the groove side of the bolster, said guide member is retained in position within the recessed column. It is preferred, however, to fasten the guide member in position in the recessed part of the column, and for this purpose I have shown each guide member as being held in position by a transverse bolt, I, which passes through appropriate openings, i, which are provided in the channeled column so as to open into the recess, h.

From the preceding description, it will be understood that the guide members, G, are fastened in positions on the columns, c, c', prior to introducing the bolster, F, into the vertical opening of the side frame. When such bolster is introduced, its grooved end portion passes into the aforesaid vertical opening below the guide members, G, after which the bolster, F, is raised. During the elevation of the bolster the guide members, G, enter the grooves, f', thus bringing the guide members into co-operative relation to said bolster. The springs are now inserted in position between the spring plank and the underside of the bolster, and, if desired, proper spring seats are employed for engagement with said springs.

As shown in Figs. 2 and 3, the side frame is provided with brake-beam hangers, J, which are preferably cast integral with the top member, a, and the vertical columns, c, c'. These hangers extend from one side of the frame, and to the lower portion of each hanger is connected a stirrup, j, by means of a bolt, j'.

Having thus fully described the invention, what I claim as new, and desire to secure by Letters Patent is:

1. In a car truck, a side frame provided with columns, each having a recess, guide blocks held in said recesses and extending forwardly from said columns into the space between them, the width of each block being equal substantially to the width of the face of the column, and a bolster co-operating with said guide blocks.

2. In a car truck, a side frame provided with columns, each having a recess, a single guide block seated in the recess of each column, the width of said guide block being equal substantially to the width of the face of said column, said guide blocks extending inwardly beyond the faces of the respective

columns and into the space between them, and a bolster co-operating with said guide blocks.

3. In a car truck, a flanged bolster, a side frame provided with parallel columns, each column being of channeled cross section at its lower part and provided above said channeled part with a recess which opens through the face of said column, a guide having a narrow part seated in said recess of each column and extending forwardly from the face thereof, and a transverse bolt for securing one guide block fixedly in position on the column, the exposed part of said guide block being equal in width substantially to the face of the column.

4. In a car truck, a side frame provided with columns, said columns having recesses in their opposing faces, guide blocks inset in said recesses and extending forwardly of the faces of the columns, the exposed part of each guide block being equal in width to the face of the column beyond which projects said exposed part of the block, and a bolster co-operating with said guide blocks.

5. In a car truck, a side frame provided with columns, a guide block on each column and extending forwardly of the face thereof, a flanged bolster co-operating with the guide blocks, each guide block being substantially equal in width to the face of the column, and transverse bolts passing through the columns for securing the guide blocks fixedly in position thereon.

6. In a car truck, a side frame provided with parallel columns, each provided with a recess, said recesses being in the opposing faces of the columns, guide members seated in said recesses and projecting beyond said opposing faces, and a bolster co-operating with said guide members.

7. In a car truck, a side frame provided with columns, each having a recess, a guide block filling said recess of each column and extending therefrom into the space between said columns, a bolt separate from the frame for fixedly retaining each guide block in position, and a bolster co-operating with said guide block.

8. In a car truck, columns provided in their opposing faces with recesses, guide blocks extending forwardly from the opposing faces of the columns and into the space between them, each guide block having a reduced portion secured in the recess of one column, and a bolster co-operating with said guide blocks.

9. In a car truck, parallel columns provided in their opposing faces, at the upper part thereof, with recesses, guide blocks seated in said recesses and extending forwardly from said faces of the columns, the width of each block being equal substantially to the face of the column in which said block is seated, means separate from the

columns for retaining said guide blocks in position, and a bolster engaging slidably with said guide blocks, the lateral thrust of the bolster being taken up solely by the 5 guide blocks and the columns to which said members are secured.

In testimony whereof I have signed my

name to this specification in the presence of two subscribing witnesses:

EDWIN H. BENNERS.
